THERAPEUTIC DEVICE

Jack Seikowitz, New York, N. Y.

Application July 25, 1941, Serial No. 404,063

11 Claims. (Cl. 21—110)

This invention relates generally to therapeutic devices.

It is an object of the present invention to provide a simple, practical and efficient apparatus capable of producing a mixed dry charge of air and medicament in gaseous form under controlled or regulated temperature and pressure.

It is another object of the present invention to provide a selectively temperature and pressure controlled volatilizer for the treatment of certain ailments and diseases of the human body.

A further object of the present invention is to provide an apparatus of the above-mentioned type which may be produced as a self-contained unit.

Yet another object of the present invention is to provide a fume-generating and inhaling device in which all moisture has been completely removed thereby providing for dry medicated fumes.

A still further object of the present invention resides in the provision of an apparatus of the aforesaid type simple in manipulation and operation and wherein the relation of heat, fumes and air can be closely controlled.

This invention accordingly consists in the features of construction, combination of parts and in the unique relations of the members and in the relative proportioning and disposition thereof; all as more completely outlined herein.

The features of novelty which is believed to be characteristic of the invention are set forth with particularity in the appended claims. The invention, itself, however, both as to its fundamental principles and as to its particular embodiments, will best be understood by reference to the specification, in which there is described, by way of example only, and not in limitation, certain ways in which the invention may be practiced.

To enable others skilled in the art so fully to comprehend the underlying features thereof that they may embody the same by the numerous modifications in structure and relation contemplated by this invention, a drawing depicting a certain form of the invention has been annexed as a part of this disclosure, and in such drawing like characters of reference denote corresponding parts throughout all the views, of which:

Fig. 1 is a side-elevational view in section (partly diagrammatic) of an apparatus made in accordance with the invention;

Fig. 2 is a top plan view of Fig. 1.

Referring now more particularly to the drawing, the apparatus is generally indicated by the

5 numeral 10. This apparatus may be divided into four sections A, B, C and D. A tank 11 containing the medicament, rests on a heating element 12 in compartment A; a conventional pressure tank 13 with its compression mechanism 14 including the usual motor 15, and also pump, safety valves, etc. (not shown) are located in compartment B. Compartment C contains the baffle plates 16, 17 which act as condensing means, causing any moisture in the vapors to condense as the fumes pass along the surfaces of these baffles 16, 17. Any moisture thus condensed will accumulate on the inclined bottom 18 ready to be drawn off by means of a cock 19. Fumes F now pass through passage 20 into the fume chamber D, from whence the fumes will flow into a suitable hose 21 to finally be ejected through nozzle 22. The entire apparatus theretofore described is preferably contained in a housing or container 23, having end walls 24, 25, side walls 26, 27, bottom 28, top 29 and partitions 30, 31, 32. The housing may be supported on suitable legs 33 having swivel rollers 34 so that the apparatus may be conveniently transported from place to place.

25 At end wall 24 is located filling means 35 for the medicament to be placed within tank 11. This filling means may comprise a funnel 36 having a cover 37 and a suitable valve 38.

Secured to top of tank 11 is a pressure gauge 39. The flow of fumes generated in tank 11 by means of heating element 12 pass through pipe 40 into a manifold 41. This flow is controlled by the valve 42, at 43, air pressure generated in tank 13 is supplied through pipe 44 into manifold 41, this air pressure being controlled by a valve 45. The combined pressure within the manifold 41 can be read by means of a gauge 46, and the temperature may be read by means of a thermometer 47. The now mixed air and fumes pass through a control valve 48 into chamber 49, from whence the fumes flow downward until they reach passage 50 close to the inclined bottom 18, and then flow upward between baffle plates 16, 17 into passage 20 having a control valve 51 which regulates the pressure of the now completely dried fumes in the compartment D and from whence the fumes pass through the hose 21 and nozzle 22 into the atmosphere.

45 It is understood that the patient to be treated may be resting on a bed 52 covered by a tent 53, indicated in broken lines.

The construction as shown permits the formation of an extra compartment 54 which may be utilized for storage of the hose 21 when not in use.

The electrical supply to heating element 12 and to compressor motor 15 may be controlled by the switches 55, 56, respectively. It is understood that suitable signal devices, such as, electric lamps, may be applied to the apparatus to indicate the various parts being in operation.

The apparatus just described is intended for external or internal medical treatment of the body; and may also be employed for fumigating purposes.

The operation of the device is as follows: Water and chemical in correct proportion and in the desired amounts are inserted into tank 11 through funnel 36, after which valve 38 is closed. The heating element 12 is put in operation vaporizing the contents of tank 11, thus producing medicated steam. The compressor 14 is put in operation to create the required amount of air pressure within tank 13. After the pressure in tanks 11 and 13 have reached the desired amounts, valves 42, 45 are opened sufficiently to permit the correct proportion of medicated steam and compressed air to reach the manifold 41. The combined pressures are measured on gauge 46, while the temperature is read on the heat indicator 47. Valve 48 is now opened, permitting the fumes F to pass into chamber C, where fumes F, on account of passing along the walls of a series of baffle plates 16, 17, are free of any moisture contained therein on account of condensation of the moisture on the surfaces of these baffle plates. This condensation will collect on the inclined bottom wall 18 to be drawn off by cock 19. The now completely dry fumes will flow, after opening valve 51, into chamber D and from there the dry fumes will flow through hose 21.

It can be readily seen that the pressure and temperature of the fumes entering chamber C may be regulated by controlling the supply of compressed air coming from tank 13 or the heated medicated fumes coming from tank 11, respectively.

It has been found from actual experience that a device of the character heretofore described is very efficient for the treatment of colds, neuralgia, inflammation of and pains in the joints, muscles, throat, nose and ears, skin infections, swellings, etc. By using the proper medicament and controlling the temperature and pressure of the developed fumes, the spray may be applied internally, or externally, directly upon the ailing part, or the spray may be made to enter an enclosure, such as, a tent in which the patient is reposed. The device may be employed in conjunction with conventional devices, such as, respirators, inhalers, etc.

I claim:

1. A therapeutic device comprising a chamber adapted to receive a fume producing substance, means for heating said substance, means for producing air under pressure, means for receiving said air and heated fumes from said fume producing substance, means for controlling the relative amounts of said heated fumes and said air in said receiving means, a second chamber connecting with said receiving means through which controlled heated fumes and air may flow, said second chamber being greater in volume than the volume of said receiving means and an outlet for said second chamber.

2. A therapeutic device comprising a chamber adapted to receive a fume producing substance, means for heating said substance, means for producing air under pressure, means for receiv-

ing said air and heated fumes from said fume producing substance, means for controlling the relative amounts of said heated fumes and said air in said receiving means, a second chamber connecting with said receiving means through which the heated fumes and air mixture may flow, said second chamber being greater in volume than the volume of said receiving means, means within said second chamber upon which said mixture may impinge, and an outlet for said second chamber.

3. A therapeutic device comprising a chamber adapted to receive a fume producing substance, means for heating said substance, means for producing air under pressure, means for receiving said air and heated fumes from said fume producing substance, means for controlling the relative amounts of said heated fumes and said air in said receiving means, a second chamber connecting with said receiving means through which the heated fumes and air mixture may flow, said second chamber being greater in volume than the volume of said receiving means, means within said second chamber upon which said mixture may impinge, a third chamber communicating with said second chamber, said third chamber being less in volume than the volume of said second chamber and an outlet for said third chamber.

4. A therapeutic device comprising a chamber adapted to receive a fume producing substance, means for heating said substance, means for producing air under pressure, means for receiving said air and heated fumes from said fume producing substance, means for controlling the relative amounts of said heated fumes and said air in said receiving means, a second chamber connecting with said receiving means through which the heated fumes and air mixture may flow, said second chamber being greater in volume than the volume of said receiving means, means within said second chamber upon which said mixture may impinge, a third chamber communicating with said second chamber, said third chamber being less in volume than the volume of said second chamber, means for controlling the flow of said mixture from said second chamber to said third chamber, and an outlet for said third chamber.

5. A therapeutic device comprising a chamber adapted to receive a fume producing substance, means for heating said substance, means for producing air under pressure, means for receiving said air and heated fumes from said fume producing substance, means for controlling the relative amounts of said heated fumes and said air in said receiving means, a second chamber connecting with said receiving means through which the heated fumes and air mixture may flow, said second chamber being greater in volume than the volume of said receiving means, means within said second chamber upon which said mixture may impinge, a third chamber communicating with said second chamber, said third chamber being less in volume than the volume of said second chamber, means for controlling the flow of said mixture from said second chamber to said third chamber, an outlet for said third chamber, and a flexible tubular member connected to said outlet.

6. A therapeutic device comprising a chamber adapted to receive a fume producing substance, means for heating said substance, means for producing air under pressure, means for receiving said air and heated fumes from said fume

producing substance, means for controlling the relative amounts of said heated fumes and said air in said receiving means, a second chamber connecting with said receiving means through which the heated fumes and air mixture may flow, said second chamber being greater in volume than the volume of said receiving means, means within said second chamber upon which said mixture may impinge, a third chamber communicating with said second chamber, means for controlling the flow of said mixture from said second chamber to said third chamber, said third chamber being less in volume than the volume of said second chamber, an outlet for said third chamber, and a receptacle housing all of said means and said chambers.

7. A therapeutic device comprising a chamber adapted to receive a fume producing substance, means for heating said substance, means for producing air under pressure, means for receiving said air and heated fumes from said fume producing substance, means for controlling the relative amounts of said heated fumes and said air in said receiving means, a second chamber connecting with said receiving means through which the heated fumes and air mixture may flow, said second chamber being greater in volume than the volume of said receiving means, means within said second chamber upon which said mixture may impinge, an inclined platform in said second chamber, an outlet in said second chamber adjacent said platform, a third chamber communicating with said second chamber, said third chamber being less in volume than the volume of said second chamber, means for controlling the flow of said mixture from said second chamber to said third chamber, and an outlet for said third chamber.

8. A therapeutic device comprising a chamber adapted to receive a fume producing substance, means for heating said substance in said chamber, passage means for the heated fumes from said chamber, a manifold connecting with said passage means, means for controlling the flow of said fumes in said passage to said manifold, means for producing air under pressure, passage means for said air between said latter means and said manifold, means for controlling the pressure of said air into said manifold, a second chamber communicating with said manifolds, said second chamber being greater in volume than the volume of said manifold, a control valve through which the air and fume mixture may pass into said second chamber, and an outlet for said second chamber.

9. A therapeutic device comprising a chamber adapted to receive a fume producing substance, means for heating said substance in said chamber, passage means for the heated fumes from said chamber, a manifold connecting with said

passage means, means for controlling the flow of said fumes in said passage to said manifold, means for producing air under pressure, passage means for said air between said latter means and said manifold, means for controlling the pressure of said air into said manifold, a second chamber communicating with said manifold, said second chamber being greater in volume than the volume of said manifold, a control valve through which the air and fume mixture may pass into said second chamber, means within said second chamber upon which said mixture may impinge, and an outlet for said second chamber.

10. A therapeutic device comprising a chamber adapted to receive a fume producing substance, means for heating said substance in said chamber, passage means for the heated fumes from said chamber, a manifold connecting with said passage means, means for controlling the flow of said fumes in said passage to said manifold, means for producing air under pressure, passage means for said air between said latter means and said manifold, means for controlling the pressure of said air into said manifold, a second chamber communicating with said manifold, said second chamber being greater in volume than the volume of said manifold, a control valve through which the air and fume mixture may pass into said second chamber, means within said second chamber upon which said mixture may impinge, and an outlet for said second chamber.

11. A therapeutic device comprising a chamber adapted to receive a fume producing substance, means for heating said substance in said chamber, passage means for the heated fumes from said chamber, a manifold connecting with said passage means, means for controlling the flow of said fumes in said passage to said manifold, means for producing air under pressure, passage means for said air between said latter means and said manifold, means for controlling the pressure of said air into said manifold, a second chamber communicating with said manifold, said second chamber being greater in volume than the volume of said manifold, a control valve through which the air and fume mixture may pass into said second chamber, means within said second chamber upon which said mixture may impinge, an inclined platform in said second chamber, an outlet in said second chamber adjacent said platform.

JACK SEIKOWITZ.
